CLOTHESLINE FIXTURE

Fred C. Curtis, Vallejo, Calif.

Application April 11, 1945, Serial No. 587,759

4 Claims. (Cl. 211—119.18)

1

This invention has reference to clothes lines and has for an object to provide means for preventing laundered material from becoming tangled up in the line pulley.

Another object of the invention is to provide a clothes line fixture including a reel, a guard for the line operating therein and a tensioning device for the line.

Other features and advantages will become more readily apparent from the following description and the accompanying illustrative drawings in which:

Figure 1 is an elevational view of my invention shown in operational position.

Figure 2 is a top plan view of one end thereof, looking in a direction of the arrows 2—2.

Figure 3 is a section on line 3—3 of Figure 1.

Figure 4 is an enlarged detail view of one part of my device.

In the accompanying drawings, as above enumerated and in the following specification, like characters of reference indicate like parts throughout and the numeral 10, indicates a clothes line fixture and which consists of a clothes line reel 11, a flexible clothes line guard 12 having a terminal portion 13, a clothes line tensioning device 14, and a brace member 15. The housing 16 of the reel is provided with a tubular mouth or discharge spout 17 for guidingly receiving and dispensing the flexible covering 12. As shown in Figure 3, the sheathing 12 is split on its under side as at 20, in order to permit said portion to drop down over the line 21, connected to post 25 by the tensioning device 14.

Attached to the opposite sides of the housing 16, are brace arms 26 and 27, the lower ends of which are fixed to the arms 28 and 29 respectively, of an inverted U-member 30, which seats over the member 18, adjacent the end thereof, whereby the members 18 and 19, are held securely in place.

The covering member 12 is formed as a flexible tube of suitable material, and is slotted throughout its entire length, whereby the covering may be fed by hand from the reel 11, through the U-shaped guide 30 and onto the clothes line 21 until it covers the same to any desired length. Laundry may now be hung upon the covering 12 and the encircled clothes line 21 in the usual manner, protecting the clothes from soiling by dust or dirt upon the exposed clothes line. Winding the reel 11 will cause the retrogression of

the member 12 and any wash attached thereto, the guard 12 being wound upon the reel and protected by the housing when not in use.

At this point, I desire to explain that the flexible tube, which is primarily to be wound of wire, is adapted to be pushed out over the tight wire, by hand and can be wound back by the crank, that is, if it has a tendency to tangle on the drum when pulled back by hand. The tube is formed by a single wire folded upon itself to form a ribbon-like band and having the folds extending in parallelism and transverse said ribbon, with the marginal edges of the ribbon being then folded inward to form a tube having a longitudinal slot at one side. The transverse folds of the wire give longitudinal flexibility to the tube.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to, in actual practice, if desired.

Having now described my invention that which I claim as new and desire to procure by Letters Patent is:

30. 1. The combination of a reel, a housing therefor having a mouth, a flexible tube extending through the mouth and extending horizontally and embracing a clothesline, means for supporting said clothesline, said flexible tube being split, 35 a tensioning device for the line carried by said means, and a brace member secured to said housing including a U-member straddling said tube adjacent to the horizontal portion thereof.

2. The combination of a reel, a housing therefor having a mouth, a flexible tube extending through the mouth and extending horizontally and embracing a clothesline, means for supporting said clothesline, said flexible tube being split, 40 and a tensioning device for the line carried by said means and connected thereto at the rear of said split tube.

3. The combination of a reel, a housing therefor having a mouth, a flexible tube extending through the mouth and extending horizontally and embracing a clothesline, means for supporting said clothesline, and said flexible tube being split.

4. The combination of a reel, a housing therefor having a mouth, a flexible tube extending through the mouth and extending horizontally and embracing a clothesline, means for supporting said clothes line, said tube being split for removably embracing a clothesline.

FRED C. CURTIS.
